CLAIM

The ornamental design for a beverage pod storage device, as shown and described.

DESCRIPTION

FIG. 1 is a perspective view of a beverage pod storage device showing the new design;
 FIG. 2 is a front elevational view thereof; the rear elevational view being an identical mirror image thereof;
 FIG. 3 is a left side elevational view thereof; the right side elevational view being an identical mirror image thereof;
 FIG. 4 is a top plan view thereof;
 FIG. 5 is a bottom plan view thereof;
 FIG. 6 is a cross-sectional view taken along line 6-6 of FIG. 4; and,
 FIG. 7 is a cross-sectional view taken along line 7-7 of FIG. 4.

The broken lines shown in the figures represent portions of the beverage pod storage device that form no part of the claimed design.
